TOY TYPEWRITER

Samuel I. Berger, Newark, N. J.

Application November 2, 1945, Serial No. 626,199

18 Claims. (Cl. 197—47)

It is among the objects of the present invention to provide a front strike toy typewriter which will type satisfactorily substantially all of the parts of which are of sheet metal and rod stock and which is yet of rugged construction, which shall generally simulate a portable typewriter in its appearance, and which in use shall simulate the action and sound of such portable typewriter.

Among the features of the present invention are the mounting of the type wheel in a carriage pivoted to a standard mounted on the base, and a type lever pivoted to the standard, operating through a transmission to tilt the carriage with its type wheel forward for typing against the front of the platen.

A selector arm moves the type wheel about its axis in the carriage for selecting the character to be typed, said arm being pivoted on the carriage mount and operating through a gear transmission to rotate the type wheel, the latter having a ratchet wheel coaxial and rigid therewith held by a spring urged pawl to maintain the type while in its set position, said pawl being released in the initial movement of the selector arm, preparatory to selective rotation of the type wheel.

The type lever has associated therewith a rocking disk which is connected by a rod to an escapement unit coacting with a rack lengthwise of the platen and preferably that disk is also alternatively under control of a spacer bar at the front of the base.

In the accompanying drawings, in which is shown one of various possible embodiments of the several features of the invention,

Fig. 1 is a perspective view of the toy typewriter.

Fig. 2 is a view in transverse cross section taken on line 2—2 of Fig. 1.

Fig. 3 is a view similar to Fig. 2 viewed from the left rather than from the right of the line 2—2 in Fig. 1.

Fig. 4 is a sectional view taken on line 4—4 of Fig. 3.

Fig. 5 is a longitudinal sectional view taken on line 5—5 of Fig. 4.

Fig. 6 is a fragmentary view similar to Fig. 5, showing the relation of the parts in typing position.

Fig. 7 is a fragmentary view similar to Fig. 6, showing the spacer bar operation.

Fig. 8 is a detail sectional view taken on line 3—3 of Fig. 2 in normal setting.

Fig. 9 is a view similar to Fig. 8, showing the escapement operation.

Fig. 10 is a view in transverse section taken on

line 10—10 of Fig. 2, showing the platen construction.

Fig. 11 is a view in transverse cross section taken on line 11—11 of Fig. 10,

Fig. 12 is a transverse sectional view taken on line 12—12 of Fig. 10,

Fig. 13 is a detail elevation showing the type selector arm in type wheel release position, and

Fig. 14 is a transverse sectional detail view taken on line 14—14 of Fig. 2.

Referring now to the drawings, the toy typewriter has a sheet metal base B comprising a short front wall 15, a higher rear wall 16, trapezoidal end walls 17 and an upwardly inclined platform 18 upon which is desirably imprinted the keyboard 19 of a conventional typewriter. The platform is desirably stiffened by a central channel bar 18' extending from the front to the rear wall thereof. Upon the rear part of the base B is desirably riveted as at 20, a sheet metal strip presenting inturned edges 21 forming tracks for slidably mounting the platen P to be described hereinafter, which has outturned edges 22 riding in said tracks.

Centrally upon the inclined base is mounted the type and type-actuating mechanism. This construction comprises a standard S, preferably a U-shaped sheet metal piece, the base or cross-bar 23 of which is affixed as by clinching at 23' to the base and the side walls 24 and 25 of which rise from said base.

Between the standard walls 24, 25 is a carriage C, said carriage being desirably a U-shaped piece also of sheet metal, the legs 26 of which are near the respective side walls of the standard and pivoted about a cross shaft 27. The carriage has a rotatable axle 28 therethrough rigidly mounting the type heads which are desirably on a type wheel T of construction conventional in toy typewriters, in which the rim 29 bears the sequence of letters, numerals and punctuation marks 30. The conventional inking roller 31 is on a sleeve 32 between the arms of a bail 33 pivoted about axle 28 and is held in place by removable spring 45 fork 34, one leg of which extends through sleeve 32, both legs passing through slots 35 in the bail arms and one of said legs being hooked over at 36. The bail 33 is held in fixed position by a wire 37 hooked into one bail arm at 38 and anchored to the base B at its opposite end at 39,

for convenience at eye 40 on the fixed escapement box 41. The inking roller can readily be replaced by removal thereof with the wire holder therefor in manner no part of the present invention.

For rotating the type wheel to select the letter, numeral or mark to be typed, a selector arm 41 is provided, which arm is rigidly affixed to one end of the carriage-mounting cross shaft 27 for rocking the latter. Rocking of the cross shaft 27 effects rotation of the type wheel T through a transmission which comprises a sector gear 42 affixed to the opposite end of cross shaft 27, preferably at the exterior of the standard wall 25. Sector gear 42 meshes with a pinion 43 rigid with the type wheel axle 28. The carriage side wall 26 has an outstanding pin 44 through an arcuate slot 45 in the sector, the ends of the arcuate slot limiting the displacement to one complete rotation of the pinion and of the type wheel T 15 affixed thereto.

To secure the type wheel in the position of adjustment effected by the mechanism just described, a ratchet and pawl arrangement is preferably provided, including a ratchet wheel 46 affixed to the end of the type wheel axle 28 adjacent the selector arm 41. Restraining ratchet wheel 46 is a pawl tooth 47 that projects outward from near the outer end of a pawl plate 48 pivotally affixed as by rivet 49 against the carriage wall 26. The outer end of pawl plate 48 overlaps the standard wall 24. The pawl tooth 47 is urged to mesh with the ratchet wheel 46 by a coil spring 50 anchored at one end to lug 51 on the carriage and at the other to lug 52 on the pawl plate.

The pawl tooth 47 is released from locking position preparatory to rocking selector arm 41 about its pivot for the desired type setting, by equipping said arm 41 with a slide member 53 extending longitudinally thereof and affixed to said arm by pins 54 slidable along corresponding elongated slots 55 in the selector arm 41. The slider member 53 carries the selector button 56 at the outer end thereof, and the inner toe end 57 of said slider member is in the path of an outstanding lug 58 integral with the pawl plate 48 which lug is curved about the shaft 27 and cut away at 59 to permit free movement of the ratchet wheel 46. Desirably a pin 60 protruding from the carriage and sliding in an arcuate slot 61 in said pawl plate 48, guides engagement and release of pawl tooth 47.

For effecting the typing operation with the type wheel selectively set as described, a type lever L is provided, which is preferably of sheet metal and includes a hand-operated cross bar 62 with a pair of lateral lever arms or wings 63 integral therewith, extending rearward therefrom and pivoted about a cross shaft 64 near the forward part of the standard S. The rear ends of the lateral lever arms are linked to the carriage C to rock the same forward about its pivot 27 for typing. To this end a cross pin 65 through the rear part of the type lever arms 63 extends through lateral links 66 desirably adjacent the respective arms 63. Links 66 are desirably connected by cross bar 67 into one unitary piece and are pivoted about cross pin 68 between the side walls 26 of the carriage C.

Preferably the type lever L is normally maintained in its raised or inactive position by a leaf spring 69 anchored at one end to the base platform 18 and conformed at the other as at 70 to the convex under face of the type lever cross bar. To prevent looseness, links 66 are extended, as shown at 66', to bottom against platform 18 under the expansion of spring 69.

Normally the carriage C is locked in inactive position, to which end a hook 71 formed at the upper edge of one lever arm 63, rides over an 75

outstanding lug 72 at the corresponding side 26 of the carriage C. Desirably the pin 65 is disposed in elongated slots 73 in the link arms 66 to afford a lost motion connection along which the initial depression of the type lever L occurs to clear the hook 71 from the lug 72 before the forward tilting of the now released carriage C takes place.

Preferably the typing mechanism described is enclosed in a unitary sheet metal hood H of ornamental character, the side walls 74 of which have outstanding foot ledges 75 affixed as by screws 76 to the platform 18. The sides 74 of the hood are connected by a unitary arcuate face plate 77 terminating at an edge 78 through which the cross bar 62 of the type lever L protrudes. The selector button 56 protrudes from the arcuate face plate 77 through an elongated slot 79 therein along which rides the slide lever 53. The face plate 77 is reinforced by a cross strip 80 between the otherwise open ends of the slot 79. The face plate has imprinted thereon, as shown, the sequence of letters, numerals and punctuation marks along which a sheet metal pointer 81 rigid with the button 56 rides for selective setting of the type wheel T.

Desirably a spring wire 32' anchored at its upper end to hood H presses outwardly against sleeve 32 and thereby normally holds the inking roller 32 out of contact with the type wheel as best shown in Fig. 5.

The type lever L also controls the operation of the escapement for stepping forward the platen. To this end there is rotatably mounted upon the type lever mounting cross-shaft 64, an escapement operating rocking disk 82, through an aperture 83, in which is hooked the forward end of a rod 84 extending rearward therefrom and actuating the escapement within case 41. The rocking disk 82 is actuated by a tension link 85 pivoted at one end about pin 68 on the carriage C and pivoted by pin 86 at its other end near the periphery of the disk 82, so that the disk is caused to rock backward about cross shaft 64 in the forward rocking movement of the carriage C and thereby pulls the rod 84 forwardly for actuating the escapement.

The escapement may be of any of a variety of forms, one desirable construction shown being that of my prior Patent No. 2,007,359, dated July 9, 1935, and which, therefore, need be but briefly described. The escapement may include an operating bell crank lever 87 pivoted by rivet 88 to the face of the escapement case 41, to the arm 87' of which is affixed the escapement operating rod 84. To the arm 87' of said bell crank lever is pivoted at 89 the escapement operating lever 90 which extends longitudinally of the case 41 and has the toothed end 91 protruding rearward from the case. The detent pawl member 92 extends between the bell crank lever 87 and the operating pawl 90, transversely of the case 41 and is guided through slots 93 and 94 in the side walls of the case and is urged to normal detent position by a leaf spring 95 anchored at the exterior of the case 41 and reacting against the downturned end or root 96 of said member 92. A coil spring 97 is anchored at one end to a hook 98 on the pivoted end of the operating pawl 90 and at the other to hook 99 on the case.

The toy typewriter also desirably has a spacing lever near the front thereof by which the escapement is, of course, also operated. This lever is desirably a sheet metal plate 100 affixed about the correspondingly frame-shaped end 101 of a

wire 102 extending downward through an aperture 103 in the platform 18 and across the entire width of said platform and is pivoted desirably at its outturned end 104 in a sleeve 105 on the rear wall 16 and is urged upwardly by a leaf spring 106 riveted at 107 to the rear wall 18 and engaging said wire at its end. Looped about a notch 108 in said wire 102 is an upstanding operating wire 109 which is hooked at 110 into the escapement operating rocking disk 82. To permit operation of the disk by the type lever independently of the spacer bar, the hook 110 passes through an elongated arcuate slot 111 in the disk 82 and similarly to permit movement of said disk by the spacer bar independently of the type lever, the pin 86 of the tension link 85 passes through an arcuate slot 112 in said disk 82.

The platen, desirably of sheet metal comprises a channel base 113, the forward wall of which has transverse slot indentations 114 forming the rack. Affixed to the ends of said channel plate are sheet metal end plates 115, desirably flanged at 116 and embracing the extremities of the cylindrically curved sheet metal plate 117, which simulates the platen. The inner edge of sheet 117 is turned inward as at 118 and along the forward face of said platen sheet is a strip 119 desirably of yielding rubber, of suitable hardness which takes the impact of the type.

To simulate the rotation of the platen and paper feed, a rectangular shaft 120 bearing in end plates 115 extends axially through the platen structure and has buttons 121 on the extremities thereof. Shaft 120 mounts a pair of rubber rollers 122 exposed through corresponding slots and coacting with corresponding rubber rollers 123 near the ends of a longitudinal rod 124 bearing in outstanding tongues 125 on the platen piece 117.

To simulate the ratcheting action in the platen movement, a radially crimped metal washer 126 about the square shaft 120 rides on radiating teeth 127 on the end plate 115 against the resistance of a strong leaf spring 128 anchored at 129 to said end plate and engaging the crimped washer.

Preferably the platen is also provided with a paper bail 130 of metal ribbon longitudinally of the platen 117 with arms 131 extending between the ends of the platen and the operating buttons 121 and through which the shaft 120 extends. The bail is movable about the shaft in the insertion of the paper, against the resistance of a coil spring 132 anchored at one end to the platen base and at the other near the outer end of the bail arm 131.

The operation will be briefly set forth. To select the desired character on the type wheel T, the button 56 is first depressed, thereby causing the slide member 53 to move along the selector arm 41 and its toe 57 to depress the pawl plate 48 against the resistance of spring 59, thereby to release the pawl tooth 47 from the ratchet wheel 46. With the selector slide thus depressed and the pawl released, the button 56 is then moved forward or backward, as the case may be, along the slot 79 until the pointer 81 reaches the selected character on the face plate 17. In this operation, the cross shaft 27 is rocked with selector arm 41, thereby rocking the sector gear 42 thereon to turn the pinion 43 and with it the type wheel T. Upon release of the button 56, the type wheel T remains in set position, the spring 59 on the pawl plate 48 returning the

pawl tooth 47 between teeth of the ratchet wheel 46, to lock it in place.

By depression of the type lever L, typing is now effected. At the beginning of such depression, the hook 71 becomes disengaged from the lug 72, the slots 73 permitting the required lost motion movement of the type lever. Thereupon, the further depression of the type lever against the resistance of spring 69 transmits thrust 10 through the links 66 to cross pin 68 to rock the carriage C about shaft 27, and with it the type wheel T toward printing position. The first part of the carriage rocking movement brings the type wheel into contact with the ink roller 32, 15 whereupon in the further rocking movement of the carriage the roller is moved upward through a short arc by the action of link 37, out of the path of the now inked type, which moves to typing position as best shown in Fig. 6. Thus the 20 ink is not wastefully spread over many of the type heads in the selective adjustment of the type wheel as would be the case were the wire 32' not used.

In the operation set forth, the pin 86 through 25 link 85 rocks the disk 82 rearward, thereby moving the rod 84 forward and operating the escapement in manner above described. In this action, the wire link 109 from the spacer bar 100 moves freely in the arcuate slot 111.

30 Upon release of the type lever L, spring 69 returns the same to idle position and through links 66 pivots carriage C forward about its shaft 27 to the position shown in Fig. 5, the final movement of the type lever taking up the lost motion in slots 73 to cause the lower end 66' or links 68 to bottom against platform 18, spring 32' to move the ink roller away from the type wheel and hook 71 on the type lever to lock over lug 72. Thus the machine is ready to be selectively 35 set for another typing operation, while the parts are maintained free from rattle and looseness between successive typing operations.

The spacer bar 100 may be depressed to actuate the escapement independently of the typing 45 mechanism, the operation being effected through the rod 102 against the resistance of spring 106. The upright wire link 109 will thus move the disk 82 in the same manner as does the tension link 85, such movement being permitted independently of the typing action by the advance of pin 86 in arcuate slot 112.

50 As many changes could be made in the above construction, and many apparently widely different embodiments of this invention could be 55 made without departing from the scope of the claims, it is intended that all matter contained in the above description or shown in the accompanying drawings shall be interpreted as illustrative and not in a limiting sense.

60 Having thus described my invention, what I claim as new and desire to secure by Letters Patent of the United States is:

1. A toy typewriter comprising a base, a platen at the rear thereof, a standard rising from said base, a type wheel carriage pivotally mounted on said standard, a type wheel mounted thereon in front of said platen on an axis parallel to the pivot of said carriage for rotary displacement thereof from setting to setting, means on said carriage for adjusting the setting of said type wheel, said means comprising a manually operated member having a rocking bearing mount fixed in said standard and parallel to the axis of said type wheel, a transmission between said member and said type wheel, and a type lever

pivoted to said standard for moving the carriage about its pivot to typing position.

2. The combination recited in claim 1, in which the rocking manually operated member is an arm which has a bearing mount coaxial with the pivot of the type wheel carriage.

3. A toy typewriter, comprising a base, a platen at the rear thereof, a standard rising from said base, a type wheel carriage having a horizontal pivot in said standard, a rotatable type wheel horizontally pivoted in said carriage and extending in front of said platen, a type lever pivoted to said standard, said lever having a linkage connection to said carriage for moving the type wheel to typing position.

4. A toy typewriter, comprising a base, a U-shaped standard thereon having a cross piece affixed to, and side walls rising from said base, an inverted U-shaped carriage having side walls between and adjacent the respective standard walls, a horizontal pivot in said standard walls, a rotatable type wheel straddled by said carriage and having an axle therein, a sheet metal type lever having parallel lateral wings extending rearward therefrom adjacent the side walls of the standard and pivotally mounted near the forward end of the latter, a cross pin connection between the rear ends of said lever, and links pivoted near one end thereof about said cross-pin connection, said links being rigidly connected near the other ends thereof, said cross-pin having a lost motion connection with respect to the links, the type lever having a locking tongue, the carriage a coacting locking lug and said lost motion connection permitting clearance of the locking tongue prior to rocking movement of the carriage by the lever.

5. In a toy typewriter, the combination of a base, a platen at the rear thereof, a standard on said base, a carriage mounted on said standard, a type wheel mounted on said carriage on an axis parallel to said platen, said carriage and said type wheel having parallel pivot mounts, means for locking said wheel against rotation, said means comprising a ratchet wheel coaxial and rigid with said type wheel and a pawl restraining said ratchet wheel and having a manual operating member for releasing the ratchet wheel, means coacting with said manual operating member for rotating the wheel to set it for typing any selected character, spring means for re-storing the pawl to reengage the ratchet wheel and restrain the type wheel in selected position, and spring resisted means for moving the carriage with the type wheel to typing position.

6. In a toy typewriter, the combination of a base, a platen on said base, a standard rising therefrom, a carriage movably mounted on said standard, a type wheel pivotally mounted in said carriage on an axis parallel to said platen, a spring actuated lock for holding the type wheel against rotation from character selected position, said lock comprising a ratchet wheel coaxial and rigid with said type wheel, a pawl coacting therewith and means comprising a manually operated lever for releasing the pawl and rotating the type wheel to selected position.

7. A toy typewriter, comprising a base, a standard rising therefrom, a carriage pivotally mounted on said standard, a type wheel pivotally mounted in said carriage, means for setting said wheel to type any selected character, said means comprising an arm having a pivot coaxial with that of said carriage, a ratchet wheel coaxial and rigid with said type wheel, a spring-urged pawl

tooth normally locking said ratchet wheel in any position of adjustment, said arm having an operating finger piece, means under control of the latter for releasing said pawl tooth, a gear rigid with said carriage pivot, and adapted to be rotated by the rocking movement of said arm and a pinion coaxial and rigid with said type wheel and meshing with said gear.

8. A toy typewriter, comprising a base, a standard rising therefrom, a carriage pivoted to said standard, a type wheel pivoted to said carriage, a ratchet wheel and a pinion both coaxial and rigid with said type wheel, a pawl having a pivot mount on said carriage and coacting with said ratchet wheel for locking the type wheel in selected position of adjustment, a segment gear rigid with the carriage pivot and meshing with said pinion, means for setting the type wheel, said means comprising an arm keyed to the carriage pivot, said arm having a spring returned slide member directed lengthwise thereof, with a hand operated outer extremity, said pawl being under control of said slide member for release thereof when said slide member is depressed, so that in the subsequent rocking of the depressed slide member with the arm, the rack and pinion are actuated for rotary adjustment of the type wheel.

9. The combination recited in claim 8, in which the sector gear has an arcuate slot and the carriage has an outstanding pin riding therein, the extremities of the slot determining the limits of one complete turn of the type wheel.

10. The combination recited in claim 8, in which the pawl is rigid with a sheet metal lever, and a spring connects the end of said lever to said carriage normally to urge the pawl into locking position.

11. The combination recited in claim 8, in which the slide member lengthwise of the type wheel adjusting arm thereof has outstanding pins passing through elongated slots in said arm for sliding adjustment therealong, in which the pawl tooth protrudes from a sheet metal lever and in which said sheet metal lever has an outstanding projection rigid therewith and in the path of slide movement of the inner end of the slide member.

12. The combination recited in claim 8, in which a type lever is pivoted to the standard and has a linkage connection to the carriage for moving the latter about its pivot to typing position and in which a cover piece attached to the base embraces the standard, the carriage and the type wheel, with the operating end of the type setting slide member exposed and in which said end has a pointer and the cover has the characters imprinted thereon along the path of said pointer.

13. In a toy typewriter, the combination of a base, a standard rising therefrom, a carriage movably mounted on said standard, and having typing heads movably mounted thereon, a type lever, a pivot rod therefor in the standard, a platen, an escapement for controlling the advance of said platen, a spacer bar, a rotary disk coaxial with the pivot rod, said disk being under the control both of said type lever and said spacer bar, a rod pivotally connected to said disk and extending forward therefrom to the escapement, said disk having a connection thereto from the type lever and having a second connection thereto from the spacer bar, said disk having lost motion slots at said respective connections to permit idle movement with respect to the other connection upon operation of either the type lever or the spacer bar.

14. The combination recited in claim 13, in which the spacer bar has a carrying rod extending through a slot in the base and has a right angle extension pivoted to the rear wall of the base and a leaf spring affixed to the rear of the base urges said rod upward, resiliently to maintain the spacer bar in upper position, said rod having an upstanding wire affixed thereto with its end hooked in said disk.

15. In a toy typewriter, the combination of a base, a U-shaped sheet metal standard affixed thereto and having side walls rising therefrom, an inverted U-shaped sheet metal carriage pivoted to said standard, a type wheel straddled by said carriage and pivoted thereto, a sheet metal type lever having lateral rearwardly extending wings and having a pivot rod near the forward end of the standard, a pivot pin through the rear ends of said wings, links adjacent the respective wings, pivoted to said pin at one end and pivoted to said carriage at the other, for transmitting thrust from said type lever to rock the carriage to typing position and means for manually setting the position of the type wheel, said means being pivoted to the carriage mounting pivot and having means coacting with the type wheel for rotating the latter.

16. A toy typewriter comprising a base, a slideable platen structure at the rear thereof having a fixed yielding impact strip at the front thereof, a typing mechanism in front of said platen comprising a standard, a carriage pivoted thereon having a type wheel on an axis parallel to said platen rotatably mounted thereon, means for locking said wheel against rotation, said means comprising a ratchet wheel coaxial and rigid with said type wheel and a pawl having a manually

operated member for releasing the ratchet wheel, means coacting with said manual operating member for rotating the wheel after release thereof, to set it for typing any selected character, a type lever and a transmission under control thereof for tilting said carriage with its type wheel forward about the pivot thereof for typing engagement with the forward part of the platen.

17. In a toy typewriter, a base, a type wheel having a horizontal axle, a carriage supporting said type wheel, means for moving said carriage to typing position, an ink roller near said type wheel and in the path of movement of the selected type head to typing position and a spring fixed with respect to said base at one end and reacting against said roller, near the other normally to maintain the roller out of contact with the type wheel for engagement by the latter in the forward movement of the carriage, and means actuated from the moving carriage to move the roller out of the path of further advance of the type wheel to typing position.

18. The combination recited in claim 17 in which the means actuated from the moving carriage comprises a bail pivoted at one end coaxially with the type wheel, said bail mounting the ink roller near the opposite end thereof, in which the carriage moves by a rocking action and a hood fixed to the base which mounts the ink roller deflecting spring, and in which a link pivoted at one end to the base, is pivoted to said bail at the other end and deflects the inking roller along the type wheel out of the path of typing in the course of the movement of the carriage to printing position.

SAMUEL I. BERGER.
